VACUUM PRESSURE PUMP

Bennie R. Hopkins, Flint, Mich.

Application July 30, 1940, Serial No. 348,517

5 Claims. (Cl. 230—190)

This invention relates to a vacuum pressure pump, the general object of the invention being to provide a cylinder having piston means therein equipped with valves with the parts so arranged that vacuum is produced in the cylinder at one stroke of the pump to draw into the cylinder fluid from a supply and this stroke forcing fluid previously drawn into the cylinder from another part of the cylinder, this fluid being transferred to a second part of the cylinder on the return stroke of the pump so that a charge of fluid is drawn into the cylinder on one stroke of the pump and then transferred to another part of the cylinder on the return stroke and then this fluid in said other part of the cylinder is forced from the cylinder on the next stroke of the pump.

Another object of the invention is to provide means whereby leakage of fluid by the piston means is returned to the cylinder and any leakage in the crankcase can be returned to the cylinder by manipulating a valve so that suction created by the pump will draw this fluid which has leaked into the crankcase therefrom.

This invention also consists in certain other features of construction and in the combination and arrangement of the several parts to be herein-after fully described, illustrated in the accompanying drawings and specifically pointed out in the appended claims.

In describing the invention in detail, reference will be had to the accompanying drawings wherein like characters denote like or corresponding parts throughout the several views, and in which:

Figure 1 is an elevational view of the improved pump as used with a refrigerating system.

Figure 2 is a section on the line 2—2 of Figure 1.

Figure 3 is a vertical sectional view through Figure 2.

Figure 4 is a sectional view through a valve means for taking care of leakage in the cylinder and crankcase.

Figure 5 is a view in section and in elevation of the fluid tank and the valve means located between the connection of the tank and the cylinder.

Figure 6 is a section on the line 6—6 of Figure 2.

In these views the numeral 1 indicates the crankcase of the engine and the numeral 2 indicates the cylinder which has its base 3 seated on the reduced top part of the crankcase and bolted thereto by the bolts 4, gaskets 5 being provided for forming a fluid-tight joint between the base and the crankcase. A top 6 is bolted to the upper

end of the cylinder and a gasket 7 is located between the top and the cylinder and said top has a centrally arranged depending portion 8 which may be referred to as a stationary piston. A passage 9 extends through the central part of the top and through the member 8 and a ball-type of valve 10 rests upon a seat formed by the reduced part of the bore at the lower end of the member 8. The piston is shown at 11 and has a large bore 12 extending downwardly from its top to form a cylinder for the stationary piston 8 and an upwardly opening ball valve 13 controls a passage 14 which passes from the bore 12 to the lower end of the piston 11. The valve 10 also opens upwardly. The stationary piston 8 and the piston 11 are provided with rings 15. The piston rod is shown at 16 and has an offset upper end which is bolted to the lower end of the piston 11 as shown at 17 and a plate 18 is located in the lower end of the cylinder 2 and is fastened therein by a bolt 19 and said plate has a recess 20 in a part thereof for receiving the offset portion of the piston rod when the piston 11 is in lowered position. The rod passes through a hole in the base 3 and through the packing means 21 located in an enlarged under part of the hole and the lower end of the rod is threaded into a cross head 22 having a forked lower end receiving a connecting member 23, a pin 24 connecting this member 23 with the forked lower end of the cross head. This member 23 forms part of a ring 25 which engages an eccentric or crank 26 of the shaft 27, said shaft being rotatably supported in the crankcase by means of the anti-friction bearings 28 and one end of the shaft extends through a side wall of the crankcase where it receives a pulley 29 or other member which will permit the shaft to be driven from a source of power. A plate 30 covers the opening through which the shaft passes and is fastened in place by the bolts 31 and a packing plate 32 is forced against the plate 30 by the spring means 33 which also presses a member 34 having a bearing part against the flaring part 35 of the shaft, this arrangement preventing any oil in the crankcase from leaking therefrom around the shaft.

Guide plates 36 extend vertically at opposite sides of the upper portion of the crankcase and engage slots in the cross head and each plate can be adjusted in a horizontal plane by a center bolt 37 passing through a horizontal slot 38 in the crankcase and each plate can also be adjusted toward the cross head by the upper and lower bolts 39 passing through threaded holes in the

crankcase and bearing against the outer edge of the plate.

A small tank 40 has its upper end in communication with a valve casing 41 and a tube 42 and a check valve 42' connects the outlet of the valve casing with the lower part of the cylinder 2, the pipe preferably communicating with the recess 20 in the plate 18. A valve member 43 which may be similar to that shown at 41 is in communication with the bore 9 in the top of the cylinder and a tube (not shown) is connected with the valve 43 and if the pump is used in a refrigerating system this pipe connected with the valve 43 would lead to parts of the system and then the fluid from the system would return to the tank 40 through a tube 44.

On the up-stroke of the piston 11 fluid will be drawn from the tank 40 through the tube 42 and by the valve 41 into the lower part of the cylinder 2, and then on the down-stroke of the cylinder 12 this fluid will be forced from the lower part of the cylinder by the valve 13 into the cylinder or bore 12 of the piston 11 and on the next stroke this fluid will be forced into the bore 9 by the valve 10.

A tube 45 extends from a side of the cylinder 2 and is in communication with the lower part thereof and has an enlarged outer end 46 provided with a cap 47 and a needle valve 48 has a threaded part 49 threaded in the part 46, this valve being adjusted by a wrench or the like engaged with the head 50 thereof after the cap 47 has been removed. A tube 51 connects the tube 45 with the upper end of the cylinder and a check valve 52 is arranged in the inner end of the tube 45 and closes outwardly. A second tube 53 connects the part 46 with the top part of the crankcase and communication between the tube 53 and the tube 45 is controlled by the needle valve 48.

Thus it will be seen that any fluid collecting in the top of the cylinder above the upper end of the piston 11 will be drawn through the tube 51 and the tube 45 by the valve 52 on the upstroke of the piston 11 or by pressure of the upward stroke of the piston 11 on this fluid and if fluid should leak by the piston rod into the crankcase in the form of gas or vapor this gas or vapor can be removed from the crankcase by opening the needle valve 49 so that the suction created by the piston 11 will draw the gas through the tube 53 by the open valve 48 and through the tube 45 into the lower part of the cylinder.

The packing means shown at 21 includes a cup-shaped member 54, see Figure 6, placed in the enlarged part of the opening in the base 3 with a plurality of packing disks 55 in the cup-shaped member separated by the washers 56 with a spring 57 in the bottom of the cup-shaped member pressing the washers and rings upwardly against the top of the large part of the opening. As will be seen from Figure 1 some of the rings contact the piston rod while others contact the cup-shaped member.

Further, as regards the operation, the cubic capacity of the cylinder 2 in the upstroke position of the piston 11 is approximately twice that of the bore 12 of said piston. The intake valve 42' is designed so that under the upstroke of the piston 11 twice the volume of fluid is admitted to the cylinder 2 that can be accommodated in the bore 12. Hence, on both the downstroke and upstroke of the piston 11, fluid will be forced past valves 13 and 12 and a steady flow will pass to bore 9 under normal conditions of back pressure.

It is thought from the foregoing description that the advantages and novel features of the invention will be readily apparent.

It is to be understood that changes may be made in the construction and in the combination and arrangement of the several parts provided that such changes fall within the scope of the appended claims.

Having described the invention, what is claimed as new is:

1. A pump of the class described comprising a cylinder having a closed bottom, a piston provided for reciprocatory movement in the cylinder and having a centrally arranged cylinder forming bore therein opening through its top, and a passage connecting the lower end of the bore with the cylinder, an upwardly opening valve for controlling the passage, a top for the cylinder having a centrally arranged depending part forming a stationary piston extending into the cylinder forming bore of the piston, and the top and said stationary piston having a bore passing therethrough, an upwardly opening valve controlling the communication between said bore and said passage and means for reciprocating the movable piston, means for connecting the lower end of the cylinder with a source of fluid supply and a discharge pipe connected with the upper end of the bore in the top of the cylinder.

2. A pump of the class described comprising a cylinder, a piston provided for reciprocatory movement in the cylinder and having a centrally arranged cylinder forming bore therein opening through its top, and a passage connecting the lower end of the bore with the lower end of the piston, an upwardly opening valve for controlling the passage, a top for the cylinder having a centrally arranged depending part forming a stationary piston extending into the cylinder forming bore of the piston, and the top and said stationary piston having a bore passing therethrough, an upwardly opening valve controlling the communication between said bore and said passage and means for reciprocating the movable piston, means for connecting the lower end of the cylinder with a source of fluid supply and a discharge pipe connected with the upper end of the bore in the top of the cylinder, a tube connecting the top of the chamber in the cylinder above the piston with the lower part of the chamber below the piston and said tube having an outwardly closing check valve therein in that end which is connected with the lower part of the chamber.

3. A pump of the class described comprising a cylinder, a piston provided for reciprocatory movement in the cylinder and having a centrally arranged cylinder forming bore therein opening through its top, and a passage connecting the lower end of the bore with the lower end of the piston, an upwardly opening valve for controlling the passage, a top for the cylinder having a centrally arranged depending part forming a stationary piston extending into the cylinder forming bore of the piston, and the top and said stationary piston having a bore passing therethrough, an upwardly opening valve controlling the communication between said bore and said passage and means for reciprocating the movable piston, means for connecting the lower end of the cylinder with a source of fluid supply and a discharge pipe connected with the upper end of the bore in the top of the cylinder, a tube connecting the top of the chamber in the cylinder with the lower part of the chamber and said tube having an outwardly closing check valve therein, a crank-

case connected with the lower end of the cylinder, a shaft passing through the crankcase, a piston rod connected with the movable piston and extending into the crankcase, means for reciprocating the rod from the shaft and a tube connecting the top of the crankcase with the tube leading into the lower part of the chamber and a manually operated valve for controlling communication between the two tubes.

4. A pump of the class described comprising a cylinder, a piston provided for reciprocatory movement in the cylinder and having a centrally arranged cylinder forming bore therein opening through its top, and a passage connecting the lower end of the bore with the lower end of the piston, an upwardly opening valve for controlling the passage, a top for the cylinder having a centrally arranged depending part forming a stationary piston extending into the cylinder forming bore of the piston, and the top of said stationary piston having a bore passing therethrough, an upwardly opening valve controlling the communication between said bore and said passage and means for reciprocating the movable piston, means for connecting the lower end of the cylinder with a source of fluid supply and a discharge pipe connected with the upper end of the bore in the top of the cylinder, said piston rod

5 having an offset upper end connected with the piston for causing the upper end of the piston rod to clear the lower end of the passage in the movable piston and the lower end of the cylinder having a recess therein for receiving the offset part of the piston rod when the piston is in lowered position.

10 5. A pump of the class described comprising a cylinder having a closed bottom, a piston provided for reciprocatory movement in the cylinder and having a centrally arranged cylinder forming bore therein opening through its top, and a passage connecting the lower end of the bore with the cylinder, an upwardly opening valve for controlling the passage, a top for the cylinder having a centrally arranged depending part forming a stationary piston extending into the cylinder forming bore of the piston, and the top and said stationary piston having a bore passing therethrough, an upwardly opening valve controlling communication between said bore and said passage, means for reciprocating the movable piston, means for connecting the lower end of the cylinder with a source of fluid supply, and a relief pipe open to the upper end of the cylinder and leading to the lower end of the same.
